WHAT-NOT SHELF

Robert J. Allen, Breckenridge, Tex.

Application August 19, 1957, Serial No. 47,440

Term of patent 14 years

(Cl. D33—3)

Fig. 1.

Fig. 2.

Fig. 3.

Fig. 1 is a front elevational view of a what-not shelf, showing my new design;

Fig. 2 is a side elevational view thereof; and

Fig. 3 is a top plan view.

The characteristic feature of my design resides in the inclusion in the shelf disclosed of the forwardly projecting dividers with rounded ends as shown.

I claim:

The ornamental design for a what-not shelf, as shown and described.
